BUBBLE GUN

Peter S. Gilchrist, Jr., Charlotte, N. C.

Application October 1, 1945, Serial No. 619,519

5 Claims. (Cl. 46—7)

This invention relates to a gun for producing bubbles whereby a plurality of bubbles can be formed by blowing a stream of air through a circular member which is coated with a bubble-forming solution.

Heretofore, bubble-forming devices have largely consisted of a member comprising a handle member and a ring on one end of the handle member, and this ring portion is dipped into a bubble-forming solution and then either the member is waved through the air by being seized by a hand of the operator or, in some instances, the operator blows through the ring to produce bubbles. It is impossible for the operator to direct a concentrated stream of air with accuracy through the center of the ring to produce the bubbles, and by the gun herein shown and described it is possible to center the annular or ring member with regard to the axis of the stream of air issuing from a nozzle so as to produce a plurality of bubbles in a much more efficient manner than has heretofore been possible by blowing through the annular member with a stream of air directed by the lips or by waving the bubble-forming device to cause air to pass therethrough.

It is an object of this invention to provide an apparatus having means whereby a quantity of air can be stored in a cylindrical chamber having a nozzle and a trigger member for actuating a bubble-forming member to dip it into a container having bubble-forming solution therein and to raise the member with the annular portion upwardly so as to cause the annular portion to be centered in front of and with relation to the longitudinal axis of the nozzle so that when air is emitted from the nozzle, it passes through the annular member coated with a film of the bubble-forming solution to thereby produce a plurality of bubbles without any waving of the bubble-forming device as has heretofore been the practice.

It is another object of this invention to provide a bubble-forming gun having a pivoted member adapted in one position to dip into a container containing a bubble-forming solution and, by pulling a trigger, to raise the bubble-forming member out of the bubble-forming solution and to align it with a nozzle together with means for forcing air through the nozzle to produce a plurality of bubbles when air passes through the annular member raised to operating position in front of the nozzle.

It is another object of this invention to provide a bubble-forming gun having means whereby, by the manipulation of a trigger, a bubble-

forming member can be lifted from a container containing a bubble-forming solution and disposed in front of a nozzle connected to one end of a cylindrical member with a pipe connected to the other end of the cylindrical member, the pipe and nozzle being of less cross sectional area than the cylindrical member and an operator can place a suitable tube in his mouth, the tube being connected to the pipe in one end of the cylindrical member and the nozzle being disposed in the other end of the cylindrical member, so that when air is blown by the operator into the cylindrical member and the cylindrical member having a greater cross sectional area than the bore of the nozzle member, a very much greater force can be imparted to the air as it passes through the nozzle member than if the nozzle member were on the end of the tube placed in the mouth of the operator, this enlarged chamber of the cylindrical member giving greater air power for producing very much better quality and a greater quantity of bubbles than would otherwise be the case.

Some of the objects of the invention having been stated, other objects will appear as the description proceeds when taken in connection with the accompanying drawings in which:

Figure 1 is a side elevation of the apparatus;

Figure 2 is a top plan view of the bubble gun;

Figure 3 is a view similar to Figure 1 but showing the parts in operating position;

Figure 4 is a transverse sectional view looking upward from along the line 4—4 in Figure 3;

Figure 5 is a rear end view of Figure 1 looking towards the left in Figure 1 and omitting the flexible tube;

Figure 6 is an elevation looking from along the line 6—6 in Figure 3;

Figure 7 is a sectional view taken along the line 7—7 in Figure 3;

Figure 8 is a vertical sectional view taken along the line 8—8 in Figure 6;

Figure 9 is a side elevation of a modified form of the apparatus and showing the front cover plate removed;

Figure 10 is a bottom plan view of Figure 9 and showing both side cover plates in position;

Figure 11 is a view of the reverse side of Figure 9.

Referring more specifically to the drawings, the numeral 10 indicates the gun stock, which may be made of wood, plastic, light metal, or any other suitable material. This stock has an opening 11 therethrough which the trigger finger of the operator penetrates. Mounted on top of the stock

10 is a tubular member 12 having a suitable resilient stopper 13 in one end and another stopper 14 in the other end.

In stopper 14 is mounted a smaller tube 15 to which is adapted to be secured a flexible tube 16, the free end of the tube 16 being adapted to be placed in the mouth of an operator whereby air may be blown into the tube 12. Stopper 13 has a nozzle 17 therein having a restricted passageway therethrough and through which air may issue 10 to form bubbles as will be presently described.

The tubular member 12 is secured to the top of the gun stock 10 by any suitable means such as inverted U-shaped strap members 20 and 21. The inverted U-shaped members 20 and 21 have set 15 screws 20a and 21a in their upper portions whereby they can be driven inwardly to clamp the tubular member 12 in position in the gun stock 10. The outer end of the gun stock 10 has a vertically disposed opening 22 therethrough which coincides with an enlarged portion 23 of the gun stock 10. On the lower side of enlarged portion 23 there is secured by any suitable means such as 20 nails, or screws 25 a screw-threaded jar lid 26 to which is adapted to be secured a jar or container 27 for containing the bubble-forming solution 28. This jar lid 26 has centrally disposed therein a suitable opening 29 through which a wand portion 31 may pass through the opening 22. This wand portion 31 is preferably circular and has an upwardly extending shank 34 which passes through a suitable slot 35 in a bolt 36 which penetrates a downturned portion 37 of a member 38 which is pivoted intermediate its ends as at 39. The bolt 36 has a nut 41 threadably secured thereon whereby the bolt when driven home will clamp the portion 34 in adjusted position. It is to be noted that the downturned portion 37 of member 38 has a horizontally disposed slot 43 therein through which the bolt 36 passes so that the bolt can be adjusted laterally in this slot 43 for lateral adjustment of the circular portion 31 and its shank 34.

The member 38 which is pivoted intermediate its ends as at 39, has pivoted to its rear end as at 45 one end of a trigger member 46 which is pivoted to the gun stock as at 47 and has a trigger portion 48 which is adapted to be engaged by the finger 49 of an operator.

Pivoted at one end to the trigger 48 is a tension spring 50 which is pivoted at its other end as at 51 to the gun stock. This spring tends to hold the parts normally in the position shown in Figure 1 and to return the parts to this position when the apparatus is operated.

In Figures 9, 10 and 11, there is shown a modified form of the invention in which there is provided side plates 60 and 61 between which is secured by suitable set screws 62 a handle portion 63 and spacer blocks 64, 65, and 66.

Adapted to lie on top of the handle 63 and filler blocks 65 and 66 is a tubular member 68 which is held in position by any suitable means such as inverted U-shaped strap member 69 which has screws 71 in its lower ends penetrating said filler block 65 to firmly secure the barrel or tubular member 68 in position.

The filler block 66 has a vertically disposed opening 73 therethrough, and to the lower side of this filler block is secured a screw-threaded jar lid 74 by any suitable means such as screws 75, this jar lid having an opening 76 therethrough coinciding with the opening 73 in the filler block 66.

Through these openings 73 and 76 is adapted to

pass an annular or otherwise formed portion 77 similar to the portion 31 in Figure 3, this portion 77 being on the end of a bent wire 80 which extends upwardly and then laterally and then rearwardly and then laterally again and penetrates the side cover plates 60 and 61 in a pivotal manner and has welded or otherwise secured thereto a leg or lever 82 which is adapted to have resting on the upper side thereof a crank portion 83 of a trigger lever 84 which is integral with a cross piece 85 and pivoted in the side walls 60 and 61.

The portion 85 has a downwardly extending trigger 87 which rests in an opening 88 being disposed in the side wall portions 60 and 61, so that the finger of an operator can be inserted through these openings 88 in the two side wall portions 60 and 61 for manipulating the trigger.

The screw-threaded member 74 is adapted to have threadably secured thereon a suitable jar or container 90 for containing a bubble-forming solution.

The end of the tubular member 68 has stoppers 91 and 92 therein, the stopper 91 having a piece of tubing such as glass tubing 93 therein over which is inserted one end of a flexible tube 94 shown more in detail in Figure 3. The stopper 92 has mounted therein a tubular portion 95 having a constricted passageway 96 through which air passed into the tubular member 68 through flexible tube 74 issues out of and in alignment with the annular portion 77 when it is in fully raised position by pulling the trigger 87 all the way back to depress the lever 82 to raise the portion 77 up in alignment with the passageway 96 in the tube 95.

In the drawings and specification there has been set forth a preferred embodiment of the invention, and although specific terms are employed, they are used in a generic and descriptive sense only, and not for purposes of limitation, the scope of the invention being defined in the claims.

I claim:

1. A bubble gun comprising a stock, a cylinder mounted on the stock, a tube of lesser diameter than the diameter of the cylinder connected to the cylinder through which air may be forced into the cylinder under pressure, one end of the cylinder having a restricted passageway leading therefrom, through which air is vented from the cylinder, a member pivoted intermediate its ends to the stock and having a downwardly projecting portion provided with an annulus on the lower end thereof, a trigger member pivoted intermediate its ends on the stock and having its forward end engaging the rear end of the member pivoted on the stock, a container carried by the stock below the annulus when the annulus is in raised position, said container being adapted to contain a bubble forming solution, means normally holding the annulus submerged in the solution, pressing of the trigger being adapted to raise the annulus into alignment with a stream of air issuing from the nozzle to thus allow the stream of air to pass through the annulus to form bubbles.

2. A bubble forming gun comprising a stock and an air chamber member mounted on the stock, said air chamber having a nozzle through which air can issue from the air chamber, a member 70 movably mounted on the stock and having a loop thereon, means on the stock for holding a bubble forming solution, means normally holding the loop in the solution, means on the stock for moving the loop out of the solution and into alignment with the nozzle, means for admitting com-

pressed air into the air chamber, air issuing from the nozzle passing through the loop when the loop is in alinement with the nozzle to thus form a plurality of bubbles.

3. Apparatus for forming bubbles from a solution comprising a container for the solution, a member having a loop thereon, means for normally holding the loop submerged in the solution, means for raising the loop out of the solution, and means for forcing a stream of air through the loop when it is raised out of the solution to thus form a plurality of bubbles from the solution held by the loop.

4. A bubble forming gun comprising means for holding a quantity of bubble forming solution, a movable member having a loop thereon, means

for moving the loop into the solution and withdrawing the loop from the solution, and means for forcing a stream of air under pressure through the loop to form bubbles from the solution disposed on the loop.

5. A bubble forming apparatus comprising a stock member, a container for a bubble forming solution carried by the stock member, a movable member mounted on the stock and having a loop thereon, means for moving the loop into and out of the solution, and means carried by the stock member for directing a stream of air through the loop while it is raised out of the solution for forming bubbles from the solution carried by the loop.
